UNITED STATES PATENT OFFICE.

JULIUS OLUF SORENSEN, OF FREDERIKSBERG, DENMARK.

AWNIN*G*.

SPECIFICATION forming part of Letters Patent No. 742,246, dated October 27, 1903.

Application filed January 15, 1903. Serial No. 139,224. (No model.)

To all whom it may concern:

Be it known that I, JULIUS OLUF SORENSEN, a subject of the King of Denmark, residing at Frederiksberg, in the Kingdom of Denmark, have invented a new and useful Improvement in Awnings, which improvement is fully set forth in the following specification.

The present invention refers to such an arrangement in awnings with side flaps that these when the awning is rolled up first place themselves flat on the under side of the awning, whereupon this, together with the said side flaps, is wound up smoothly upon a pole by means of a double-cord pulley arranged in such a way that the winding takes place in an easy and simple manner. A constructional form is shown on the drawings, wherein—

Figure 1 represents the awning let down. Figure 2 shows the awning rolled up half-way with the side flaps folded up below the awning. Figs. 3 and 4 illustrate details.

The awning consists of the front piece 1 and the side flaps 2. The pole 17 around which the awning is to be wound is placed above the window to be protected by the awning and carries two sheaves 3, firmly fixed upon the pole and to which the cords 4 are fastened. After being wound around the sheaves these cords run through eyes 5 and 6 and are connected to the ring 7, to which a larger ring 8 is fastened. Further, the corners 9 of the side flaps 2 are fastened to cords 10, which run through an eye of the main awning, preferably in the form of an opening 11 in the center of the awning's front piece 1, thence up and around the sheave 12, and are connected to the ring 13, whence a single cord 14 passes through the eye 15.

The cord-pulley acts in the following manner: By pulling at the cord 14 the side flaps 2 will be laid flat to the under side of the awning's front piece, as shown in Fig. 2. The ring 7 is arranged thus that the ring 13 will touch it just at this very moment. By a continued pull at the cord 14 the ring 13 will press upon the ring 7, and the cords 4 will thereby revolve the pole 17, and thus wind the awning upon it until the hole 11 has reached its uppermost position. The eye 15 is placed thus that the ring 13 will reach this

eye 15 just at this very moment. The cord 14 is now released and the ring 8 pulled until the awning is completely wound upon the pole 17 and the ring 8 has reached the button 16, upon which it is hooked, while the cords 10 at the same time will be wound around the middle of the closed awning. By this arrangement the advantage is moreover obtained that the awning can be easily and securely unrolled by unhooking the ring 8 from the button and pulling at the cord 14, whereby the cords 10, wound around the middle of the pole, will turn it round and the awning unfolded until the hole 11 comes free. The cord 14 is now released, and the awning will by its own weight unfold itself completely.

Having now particularly described my said invention and in what manner the same is to be performed, I declare that what I claim is:

1. The combination of a rod or roller, a main awning having side flaps adapted to be wound up with the awning on said roller, a cord wound around a drum or sheave on said rod or roller to rotate the same to wind up the awning, cords for folding the side flaps against the main awning one connected to each flap and passing through an eye or opening of the main awning, and engaging means moving with the side-flap cords for engaging the roller-cord to move the same after preliminary movement of the side-flap cords sufficient to fold said flaps against the main awning.

2. The combination of a rod or roller, a main awning having side flaps adapted to be wound up with the awning on said roller, a cord wound around a drum or sheave on said rod or roller to rotate the same to wind up the awning, cords for folding the side flaps against the main awning one connected to each flap and passing through an eye or opening of the main awning, and engaging means moving with the side-flap cords for engaging the roller-cord to move the same after preliminary movement of the side-flap cords sufficient to fold said flaps against the main awning, but leaving the roller-cord free to operate the roller to wind up the awning and with it the side-flap cords after the eye or opening on the main awning has reached the roller.

3. The combination of a rod or roller, a main awning having side flaps adapted to be

wound up with the main awning on said roller, cords wound at one end around a drum or sheave at each end of the rod or roller for rotating the same to wind up the awning and 5 connected at their other end to a ring or eye, cords for folding the side flaps against the main awning one connected to each flap passing through an eye or opening of the main awning and leading through the ring or eye 10 to which the roller-cords are connected and engaging means moving with the side-flap cords for engaging said ring or eye to move the roller-cords after preliminary movement

of the side-flap cords sufficient to fold said flaps against the main awning, but leaving 15 the roller-cords free to operate the roller to wind up the awning and with it the side-flap cords after the eye or opening on the main awning has reached the roller.

In testimony whereof I have signed this 20 specification in the presence of two subscribing witnesses.

JULIUS OLUF SORENSEN.
